UNITED STATES PATENT OFFICE.

RUDOLF KRAUSSÉ, OF MENTZ, GERMANY.

STREET-LAMP.

SPECIFICATION forming part of Letters Patent No. 310,209, dated January 6, 1885.

Application filed August 22, 1883. (No model.) Patented in Germany April 5, 1883. No. 22,927.

To all whom it may concern:

Be it known that I, RUDOLF KRAUSSÉ, of Mentz, in the Empire of Germany, have invented new and useful improvements in the construction of gas-lanterns for lighting streets and public places, called "lanterns for intensive lighting," which are fully set forth and described in the following specification.

My improved construction of lanterns has for its object to attain a higher lighting effect in comparison with the ordinary lanterns, at an equal consumption of gas, in connection with a quiet flame independent of or free from external disturbing influences. These advantages will be obtained, first, by the admission of air in a warmed state and in a quantity corresponding to the consumption, for which purpose the cross-section of apertures of the tubes for admitting air must be in a suitable proportion; second, by a tight locking of the lantern; and, finally, by the employment of a cap or helmet, preventing the entrance of wind; and in order that my said invention may be fully understood, I shall now proceed to describe the same more particularly, and for this purpose refer to the annexed sheet of drawings, the same letters of reference indicating the same parts in all the figures.

Figure 1 shows an external view of my improved lantern. Fig. 2 is a vertical section on the line A. B of Fig. 1. Fig. 3 shows a burner one-half of its usual size.

Above the under frame, *a*, which is provided with the roof *b*, is arranged a second roof, *c*, which is fastened at a determined distance from *b*, and which projects over and about the edges of *b*, as shown at *b'*.

In the interior of the lantern, and at a certain distance from the burner *f* and from the roof *b*, is arranged the reflector *r*, to which is closely connected the chimney *t*, with a conical extension, *s*, over which the cap *h* rises. The bottom of the lantern is closed, the panes of the sides and roof are tightly fitted, and likewise the door, when closed, should be tight and held closed by any suitable means—as, for instance, by a lever. (Indicated at *r* in Fig. 1.)

The burner *f* consists, first, of a number of

double burners, the number and size of which depend upon the capacity of the lantern; second of one single double burner, *g*; and, third, of the light-flame *k*.

In lanterns of smaller size with only one flame, the burner *g* and light-flame *k* are dispensed with. A cock, *p*, admits the gas to the burners, and it should be so arranged with reference to the different burners that, by turning it more or less, as desired, it will either admit gas to the burner *g* alone or to all the other burners around *g*, while cutting off the supply to *g*. This will be evident to any gas-fitter and needs no further explanation.

The operation of my lantern is as follows: By turning the cock *p* for one-eighth ($\frac{1}{8}$) of a circle the burner *g* will be lighted on the flame *k*, which burner alone burns in this position of the cock. If the turning of the cock is continued a further eighth ($\frac{1}{8}$) of a circle, all the other burners around the burner *g* get lighted, while *g* is extinguished. The admission of air to the flame is now effected in the way indicated by the arrows *l*. The air enters at *b'* into the space *x* between the two roofs, *c* and *b*, which space constitutes a pre-heating storage-chamber closed at its highest point or part, and in which air is stored before it takes its way downward to the interior of the lantern. The outer air enters this chamber a long distance from its top or highest point and always passes in an upward direction, as indicated by the arrow *l*, the chamber being over the whole of the under or main roof, *b*, and forming with it a space which is entirely or substantially protected against all outer currents or blasts of air. The air when rising in this chamber is already heated, and the air most heated must occupy the highest place, and at this point it comes into direct and intimate contact with the deflector, and remains there until, in consequence of the difference of gravity between the stored air and that contained in the lantern, an entering of the heated air into the lantern takes place through the apertures *i*, which may, if desired, be covered with wire-gauze. The more heated the deflector becomes the more heated also becomes the air in the upper part of this storage-cham-

ber, and it requires an increased development of heat in the interior of the lantern in order to cause the sinking down of the air. In this way the air is warmed, first, in the space *x*, 5 next in the space *y*, over the reflector, and finally directly by the radiated heat of the flame. The velocity of the admitted air depends upon the cross-section of the inlets, and upon the difference of the temperature between the entering air and the escaping gases of combustion, and also upon the height of the chimney, which is preferably as small as possible, so that the flame is in no manner disturbed. The gases of combustion escape 10 in the direction indicated by the arrows *m*. The construction of the double roof prevents the external currents of air acting upon the inlets of air, whereby the pernicious influence of wind in the direction of the arrows *n* is excluded by the cap or helm, (constructed of three roofs,) while it allows free escape to the 15 gases of combustion. It will be seen also that any external blasts of air incident to storms or sudden gusts can exert little or no agitating influence on the burning flame, because such blasts must strike against the outer roof, *c*, which has no openings whatever to admit air, the only inlet for air being below the 20 lowermost point or line of the inner roof, *b*, and this is an annular inlet surrounding the 25 lantern. This outer roof, *c*, at its lowest part, has also an inwardly-turning flange, *b'*, which extends below the roof *b*, and still further guards against any violent driving of air into 30 the space or chamber *x*, for this flange *b'* must operate to deflect such driving winds and lead them downward outside the lantern and away from the receiving-mouth of the space *x*.

My improved construction of lanterns permits the advantageous employment of double burners, (the latter very sensibly resisting the influence of currents of air,) and offers a considerable increase of lighting effect, in consequence of the preheating of air, avoiding the 40 admittance of too much air, and consequently the cooling of the reflector, which increase, after several and exact photometrical measurements, amounts to eighty-four per cent. in comparison with the effect of an ordinary burner. 45 I am aware that lanterns have been made in which the air for combustion is admitted at or near the top of the lantern-roof through a circular series of openings made for that purpose, and in a horizontal or nearly horizontal 50 direction beneath a narrow rim or band projecting horizontally, or nearly so, a short dis-

tance from a chimney, and not parallel with nor outside of the main roof; but in such construction there is no double roof such as I have shown and described, and the incoming 60 currents of air are not protected against outer violent gusts or winds, as they are by my special construction; but I am not aware that prior to my invention a street gas-lantern has been made having an external supplemental 65 roof parallel with the main roof and extending down to the plane or level of the lowest line of such main or ordinary roof, the space between the lower parallel lines of these two roofs affording the only inlet for air to support 70 combustion; nor am I aware of any such construction in which an inwardly-turned flange depends from the lowermost edge of this second or outer roof.

Having now described and particularly ascertained the nature of my invention, and the manner in which the same is or may be carried into effect, I would observe, in conclusion, that what I consider to be novel and original, and therefore claim as my invention, 75 is—

1. A lantern for gas-lighting, provided with a second roof, *c*, outside of and substantially parallel with the main roof *b*, and extending downward to the level of the lowermost line 80 of said main roof, and admitting air only between these roofs and at or below said lowermost line, the combination and arrangement of these parts serving not only to exclude the influence of external currents of air, but also 85 for the purpose of storing and preheating air for combustion, all substantially as shown and described.

2. In combination with the main roof *b* and with the exterior roof, *c*, extending down to 90 the plane or level of the lowermost line of the main roof, the inwardly-turned flange *b'*, projecting inwardly from the lower line of said roof *c*, as and for the purpose set forth.

3. In combination with the preheating chamber *x*, located between the roof *b* and a second and outer roof, *c*, the openings *i* in the main roof *b*, and the deflector *r*, the combination being and operating substantially as and 95 for the purposes set forth.

In testimony whereof I have signed this specification in the presence of two subscribing witnesses.

RUD. KRAUSSÉ.
